UNITED STATES PATENT OFFICE.

JOHN TUTIN, OF SUNDERLAND, ENGLAND.

MEANS FOR STEERING AND PROPELLING SHIPS.

Application filed April 3, 1926, Serial No. 99,537, and in Great Britain January 22, 1926.

It is known that by arranging suitably curved or inclined plates abaft a screw propeller, the rotation in the stream of water leaving the screw will cause the water to impinge on the plates in such a manner as to produce a propulsive force or reaction. This reaction is the sum of the forward components of the pressure on the one side, and the suction or defect of pressure on the other side, and it is known that the suction effect is normally the greater of the two.

Several forms of rudder have been proposed in which application is made of this principle. For example, it has been proposed to give a rudder a twisted shape, so that it partakes somewhat of the form of the thread of a quick screw, the object being that in its mean position such a rudder will present a face or faces parallel or approximately so to the water driven sternward from the screw propeller.

Another device consists in forming a counter propeller on the stern post and associating therewith a shrouded unbalanced rudder.

It has also been proposed to provide a multi-bladed counterpropeller, mounted abaft the ordinary propeller, and adapted to be swung about to port and starboard angles to divert the flow of the propulsive jet and thus control steering. Further it has been proposed to attach such a counterpropeller to an ordinary rudder.

One of the difficulties in adapting a rudder for propulsive purposes by merely twisting, inclining, or curving the plate or plates, is due to the position of the mainpiece, which would seriously interfere with the flow of water over the curved or inclined portions of the rudder, and so prevent the full development of the reaction or regenerative effect.

My invention consists of a balanced rudder comprising substantially vertical members, which differs essentially from all other known forms of rudder such as referred to, in that it is constructed of approximately conventional size and height of a mainpiece, arms extending fore and aft of said main piece and plating directly secured to the outer sides of such arms. The difficulty referred to in the preceding paragraph is, inter alia, overcome by so arranging one or more of the rudder plates to port and/or

starboard of the mainpiece that there is a reasonable clearance between such plate or plates and the mainpiece, the space offering no material restriction to the flow of water therethrough, and permitting of the complete or almost complete development of the suction effect above referred to.

I balance rudders of the type above described by extending a part or parts of the plating forward past the pivotal axis, on either the port or starboard side of the mainpiece, or on both sides.

Many forms of balanced rudder are known. They differ from the ordinary unbalanced rudder in that instead of the whole rudder area being abaft the pivotal axis, a portion is arranged forward of the axis. By this means the power required to operate the rudder is considerably reduced, since it will be seen that when the rudder is inclined at any given angle to port or starboard, the impact of the water on the forward portion will assist in turning the rudder whilst the impact on the after portion will retard the movement. The difference in the moment of these forces represents the effort which must be exerted to turn the rudder, and it can obviously be made very small. The line of action of the resultant of the above forces passes through a point known as the centre of pressure, and obviously by balancing the rudder, this point may be brought nearer to the pivotal axis.

In the case of single or multiple screw ships having the normal type of aperture stern frame, an ordinary unbalanced rudder is usually fitted, supported, at its forward end, on gudgeons attached to the stern post of the vessel. The presence of the stern post, however, makes it difficult to arrange an extension of the rudder forward of its pivotal axis. In such a case it will be seen that my invention permits of a balanced rudder being fitted where this would otherwise not be practicable, since it provides for the balancing portions of the rudder being arranged to port and/or starboard of the mainpiece in such a way as to obtain the proper range of angular movement of the rudder without fouling the sternpost. It will be seen that the separation between the plates and the mainpiece must not be less than and need not be greater than an amount sufficient to permit the rudder to clear the

sternpost at the maximum angle of helm. With such an arrangement adequate support of the rudder by pintles or otherwise at intermediate points in its height, in the ordinary way, is possible.

In cases of ships fitted with an open stern frame, an ordinary balanced rudder is usually fitted comprising two flat or tapered portions, one directly forward of the main 10 piece, and the other directly abaft the main piece. A balanced rudder constructed according to my invention, on the other hand, may be arranged substantially as described above for a vessel with an aperture stern 15 frame, with the exception that in the present case the balanced portion of the rudder would necessarily be supported at an upper bearing only, or at an upper bearing and a lower bearing only, instead of at intermediate 20 points; also, since the stern post is removed in way of the balanced portion of the rudder, the plates may, if desired be arranged nearer to the centre line of the vessel than in the corresponding arrangement with an 25 aperture stern frame. In no case is a separation contemplated between rudder plates and main piece of the order of that required for a "box" type of rudder, since it is obvious that a rudder adapted to assist pro- 30 pulsion, must be as close as possible to the vertical centre line of the screw disc.

But in order that the invention may be more readily understood and easily carried into effect it will now be further described 35 with the aid of the accompanying drawings in which one example is diagrammatically illustrated by Fig. 1. Fig. 2 representing a series of sections designated A, B, C, D, E, F, G, H and J to correspond to the lines 40 similarly designated in Fig. 1. Figs. 3 and 4 are elevations, at right angles to one another, of a detail. Figs. 5 and 6 are a diagrammatic end elevation and plan respectively of a modification.

45 As shown in Figs. 1 and 2 the rudder comprises three plates 1, 2, 3 supported on arms 4 from a shaft 5. The plate 1 is flat and directly attached to the three uppermost arms so that it is supported on both sides. 50 A right handed propeller is assumed to be employed, that is to say one which rotates clockwise when viewed from astern the ship, in which case the plate 2 will be secured to the port side of three arms 4 above the axis 55 of the propeller whilst the plate 3 is equivalently secured to the starboard side of three arms 4 below the axis aforesaid. This lower set of six arms 4 associated with the plates 2 and 3 are extended as at 4° forward 60 of the pintles 6 and the rudder post 7 which in Fig. 2 is indicated as displaced to show the angle through which the rudder can be turned, in this case about 42° to each side of the central position.

65 As will be clear from the various sections

in Fig. 2 the plates 2 and 3 are, by their arms 4, carried past the main piece 5 with clearance sufficient for the purpose already referred to.

It will be apparent from the sections in Fig. 2 that the after edges of the plates 1, 2 and 3 are not in vertical alignment but they obviously may be so if desired. Where there is discontinuation in the fore and after edges of the plates means may be provided 70 to act as guards at these places. Thus as shown in Figs. 3 and 4, the plates 2 and 3 may be secured together at the back edge of the rudder by guards 8 which will prevent ropes etc. being caught up. Another way 75 of effecting connection between the plates is to employ a plate, flat or joggled, arranged horizontally and secured to the adjacent 80 horizontal edges of the plates, as by angle bars or other means.

85 With a rudder thus constructed it will be found that the centre of pressure acts at a relatively short distance from the axis of the pintles and that its movement can be effected with greater ease.

90 Although curved plating is preferred, it will be obvious that the invention is not limited to the use thereof and further that a rudder or rudders according to the invention may be used in twin or multiple screw 95 vessels. Figs. 5 and 6 for example illustrate plates 2^b, 3^b which are inclined to the longitudinal axis of the vessel.

What I claim is:—

1. In a screw propelled ship, the combination 100 with a stern post, of pintles aft thereof, curved brackets movable about said pintles and extending both aft and forward thereof beyond the stern post, the curvature of some of said brackets being the reverse of the curvature of the others and oppositely curved plates attached to said arms and likewise extending fore and aft of the pintles and stern post, substantially as described.

2. A screw propelled ship's rudder comprising 105 a main piece, and substantially vertical members laterally displaced in relation to the main piece, one at least of such members being extended forward of the main piece leaving lateral clearance between it 110 and the main piece.

3. A screw propelled ship's rudder comprising 115 a main piece, and substantially vertical members laterally displaced so as to occupy positions at opposite sides of the main piece, such members being extended forward of the main piece, leaving clearance between them and the main piece.

4. A balanced ship's rudder comprising a main piece and plating adapted to impart a 120 contributory propulsive thrust to the vessel, characterized by the fact that at any horizontal section such plating is laterally displaced on one side only of the main piece.

5. A balanced ship's rudder adapted to 125

impart a contributory propulsive thrust to the vessel, comprising a main piece, and, at any horizontal section, laterally displaced plating, on one side only of the main piece, 5 said rudder being characterized by the fact that at one intermediate section the plating is discontinuous, the upper and lower plat-

ing being on opposite sides of the main piece respectively.

Signed at 5 Beauclerc Terrace, Sunderland, in the county of Durham, this 17th day of March, 1926.

JOHN TUTIN.
